B. M. W. HANSON.
CHUCK ACTUATING DEVICE.
APPLICATION FILED MAR. 27, 1905.

905,518.

Patented Dec. 1, 1908.

UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

CHUCK-ACTUATING DEVICE.

No. 905,518.

Specification of Letters Patent.

Patented Dec. 1, 1908.

Application filed March 27, 1905. Serial No. 252,337.

To all whom it may concern:

Be it known that I, BENGT MAGNUS WILHELM HANSON, a citizen of Sweden, residing at Hartford, in the county of Hartford and 5 State of Connecticut, have invented certain new and useful Improvements in Chuck-Actuating Devices, of which the following is a specification.

This invention relates to chucks designed 10 more particularly for use with metal-working machines, although it is not limited in scope of employment.

In chucks as ordinarily constructed, and especially those of what is known as the 15 "collet" variety difficulty is frequently experienced in causing the chuck-jaws firmly to engage the stock and to hold the same without danger of slippage, and this is particularly noticeable when unevenness occurs 20 in the surface of the stock engaged by the jaws.

My invention is designed to overcome defects heretofore existing and to provide a 25 chuck of great utility in the grasping or holding line.

Primarily the object of the invention is the provision in connection with usual means for actuating the chuck-jaws, of auxiliary devices for applying additional pressure to said jaws should the stock not be firmly held by them.

A further object of the invention is the provision in connection with the chuck-actuating spindle of auxiliary devices for imparting additional clamping action to said spindle.

A further object of the invention is the provision in connection with a chuck-spindle and chuck of a thrust-cap rigid with the 40 live-spindle, a device mounted for swinging movement on the thrust-cap, means carried by the thrust-cap for actuating said device, and means for conveying the pressure exerted by the device to the chuck-spindle.

Other objects of the invention will be hereinafter set forth.

In the accompanying drawings, Figure 1 is a longitudinal, vertical section of a chuck-spindle and chuck, and of means for rotating the same, showing my invention embodied therewith. Fig. 2 is a side elevation, the live-spindle being broken away. Fig. 3 is a side elevation of the draw-in lever detached from the thrust-cap on the spindle; and Fig. 4 is a longitudinal vertical section

of the thrust-cap, draw-in lever, and annulus forced by said lever against an abutment on the chuck-spindle.

Like numerals designate similar parts throughout the several views. 60

Referring to the drawings, the numeral 1 designates the pillow-blocks of a head-stock, in bearings of which the tubular-spindle 2 is journaled, said spindle having at its forward end an enlarged head 3, provided with 65 the usual wear-ring 4, for a purpose herein-after stated.

For rotating the spindle a gear or pulley 5 may be secured thereto in the usual manner. Located within the spindle 2 is a draw-in spindle 6, internally threaded at its forward end at 7 to engage external threads 8, of a split collet 9, said collet having a conical surface at its free end adapted to be engaged by the wear-ring 4. At its rear extremity the draw-in spindle 6 is provided with a hand-wheel 10 by which it may be manipulated, said hand-wheel being keyed at 11 to said spindle, and the hub of the same bearing at its inner end against a collar or abutment 12 rigid with the chuck-spindle. Surrounding the chuck-spindle is a loose annulus 13, the purpose of which will be hereinafter described. 80

Designated by 14 is a thrust-cap or block, which is secured by a screw 15 or otherwise to the rear end of the spindle 2, and is provided with oppositely-disposed extensions 14'. In the thrust-cap is mounted a threaded bolt 16 having an angular head 16' to which a wrench may be applied for actuating the bolt. Attached to the thrust-cap at the points 14', where it is extended, are oppositely-disposed plates 17, each having a bearing 17' at its free end. Screws 18 are 95 shown as the attaching means for said plates, but other devices for this purpose may be employed if desired.

Designated by 19 is an annular draw-in lever, and said lever is provided on its upper 100 portion with an extension 20 having a bearing-face to receive the head of the bolt 16, as shown in Figs. 1, 2, and 4. This draw-in lever is enlarged on each side at 20', and rigid with the inner side of each enlargement is a lug 21. Lateral external extensions 22 project from each side of the draw-in lever 19, and rigid with each of said extensions is a trunnion 23, the trunnions being fitted in the bearings 17' of the plates 110

17. Said draw-in lever 19 surrounds the spindle, as shown in Fig. 1, and by dotted lines in Fig. 4, and the lugs 21 thereof bear at opposite points against the sides of the 5 ring 13, as illustrated in Fig. 4. As will be observed from Fig. 4, the lugs 21 bear against the sides of the ring 13 above the pivotal point of the draw-in lever on the trunnions 23, and said lugs act upon about 10 the central parts of the sides of the ring, so that a powerful leverage is exerted upon the ring and draw-in spindle when the screw 16 is actuated, and the chuck will be compressed with great force upon the stock. A 15 pin 25 entering a groove 26 prevents independent rotation of the chuck 9.

In the operation of the invention the collet 9 is first closed upon the stock in the usual manner by grasping the hand-wheel 20 10, and rotating the draw-in spindle 6, a plain bearing-surface of said collet engaging the usual wear-ring 4 in the spindle 2, as illustrated in Fig. 1. Should the power applied by the draw-in spindle be insufficient 25 to cause the chuck-jaws firmly to engage the stock and to rotate the same without danger of slippage, it becomes necessary to apply auxiliary power to said draw-in spindle, and this is accomplished in the following manner. As illustrated in Fig. 1, 30 and as before stated, the draw-in lever 19 surrounds the spindle 6, and its extension 20 is in engagement with the head 16' of the screw 16, while the lugs 21 bear against the 35 annulus 13. It will, therefore, be seen that when the stock is not firmly held by the chuck, additional closing power may be applied to said chuck by rotating the threaded-bolt 16, and thereby forcing the pivoted 40 draw-in lever to the rear, and causing its lugs 21 to bear with greater force against the annulus 13, and as said annulus is in engagement with the collar 12 of the draw-in spindle it follows that great power may 45 be applied to said spindle to cause the chuck-jaws firmly to grasp the stock.

While the draw-in lever and the other parts of the invention are shown as of particular form, it is distinctly to be understood 50 that changes may be made therein without departure from the invention. So too, means different from the screw may be employed for actuating the draw-in lever to impart an auxiliary pressure movement to 55 the chuck-spindle. Chucks of other forms may also be employed as substitutes for the chuck shown if desired.

Having thus described my invention, what I claim is.

60 1. The combination, with a main spindle, and with a chuck and its spindle, of means for preliminarily closing said chuck; bearings carried by the main spindle; an auxiliary chuck-closer journaled in said bearings 65 and surrounding the chuck-spindle; and

means also carried by the main spindle for actuating said auxiliary chuck-closer to impart additional pressure to the chuck-jaws.

2. The combination, with a rotary main spindle, of a thrust-block rigid with said spindle; a chuck and its spindle mounted within the main spindle; means for preliminarily closing said chuck; a draw-in lever pivoted to the thrust-block, and surrounding the chuck-spindle; means carried by the 70 main spindle for actuating said draw-in lever; and means actuated by said draw-in lever for operating the chuck-spindle.

3. The combination, with a tubular spindle, of a chuck-actuating spindle mounted 80 in said tubular spindle; a chuck; a thrust-block rigid with the end of the tubular spindle; an annular draw-in lever pivoted to the thrust-block; means operated by said lever for imparting an auxiliary closing 85 movement to the chuck-actuating spindle; and means carried by the thrust-block for actuating said lever.

4. The combination, with a spindle, of a thrust-block carried at the inner end thereof; 90 a chuck; means for imparting a preliminary closing movement to the chuck; a device pivoted to the thrust block for imparting an auxiliary closing-movement to the chuck-actuating means; and a screw carried by 95 the thrust-block, one end of the screw bearing against said device.

5. The combination, with a chuck-actuating spindle, having an abutment, of a rotary spindle; a thrust-block carried by said 100 rotary spindle; a lever pivoted to the thrust-block and having a lug; and a ring on the chuck-actuating spindle, said ring bearing against said lug at a point above the axis of the lever.

6. The combination, with a chuck-actuating spindle and a rotary spindle in which it is mounted, of a thrust-block rigid with the rotary spindle; an annular lever having trunnions journaled in bearings of the thrust-block, said lever surrounding the chuck-actuating spindle; means connecting said lever and said chuck-actuating spindle; and means carried by the thrust-block for actuating 110 said lever.

7. The combination, with a tubular draw-in spindle and its chuck, of a tubular spindle in which said parts are mounted; a thrust-block rigid with the tubular spindle; an annular lever pivoted to the thrust-block, 120 and surrounding the draw-in spindle; an abutment on the draw-in spindle; a ring surrounding the draw-in spindle and engaging the abutment; lugs carried by the annular lever, and bearing against the ring; 125 and a device carried by the thrust-block for actuating the annular lever.

8. The combination, with a draw-in spindle, of a chuck actuated thereby; a tubular spindle in which the draw-in spindle and 130

- 5 chuck are mounted; a thrust-block rigid with said tubular spindle; an abutment on the draw-in tubular spindle; and means carried by the thrust-block for actuating said draw-
5 in spindle.
9. The combination, with a tubular spindle, of a draw-in spindle; a chuck actuated by said draw-in spindle; an annular thrust-block rigid with the tubular spindle, and having bearings; an annular lever having trunnions mounted in said bearings, said lever surrounding the draw-in spindle, and being provided with internally-projecting lugs; a ring surrounding the draw-in spindle; an abutment on said draw-in spindle to receive the thrust of the ring; and means carried by the thrust-block for actuating the annular lever.
10. The combination, with a tubular spindle, of a draw-in spindle; a chuck actuated 20 by said draw-in spindle; a thrust-block rigid with said tubular spindle, and having extensions; an annular lever having trunnions mounted in bearings of said extensions, and also having inwardly-projecting lugs; a ring 25 loose on the draw-in spindle; an abutment on said draw-in spindle for receiving the thrust of the ring; and a bolt threaded into the thrust-block, and one end of which bears against the annular lever.
- 30 In testimony whereof I affix my signature in presence of two witnesses.
